UNITED STATES PATENT OFFICE.

THOMAS C. JOHNSON, OF NEW HAVEN, CONNECTICUT, ASSIGNOR TO
WINCHESTER REPEATING ARMS CO., OF NEW HAVEN, CONNECTI-
CUT, A CORPORATION.

WROUGHT-METAL FOREARM FOR TUBULAR-MAGAZINE GUNS.

No. 808,375.

Specification of Letters Patent.

Patented Dec. 26, 1905.

Application filed July 3, 1905. Serial No. 268,143.

To all whom it may concern:

Be it known that I, THOMAS C. JOHNSON, a citizen of the United States, residing at New Haven, in the county of New Haven and State 5 of Connecticut, have invented a new and useful Improvement in Wrought-Metal Fore-Arms for Tubular-Magazine Guns; and I do hereby declare the following, when taken in connection with the accompanying drawings 10 and the numerals of reference marked thereon, to be a full, clear, and exact description of the same, and which said drawings constitute part of this specification, and represent, in—

Figure 1, a view in side elevation of one form 15 which a wrought-metal fore-arm constructed in accordance with my invention may assume; Fig. 2, a view thereof in rear elevation; Fig. 3, a plan view thereof; Fig. 4, a view thereof in vertical longitudinal section; Fig. 5, a view 20 thereof in transverse section on the line *a b* of Fig. 1; Fig. 6, a detached sectional view of the front tenon-piece, mounted in the front end of the fore-arm; Fig. 7, a detached view, in front elevation, of the said front tenon- 25 piece; Fig. 8, a detached view, in vertical section, of the rear tenon-piece, mounted in the rear end of the fore-arm; Fig. 9, a view in front elevation of the said rear tenon-piece; Fig. 10, a plan view of one of the modified 30 forms which the fore-arm may assume, the ends of the metal itself being bent for the production of integral tenons instead of using separately-formed tenon-pieces; Fig. 11, an enlarged sectional view of the integral front 35 tenon of Fig. 10; Fig. 12, a corresponding view showing how the metal of the fore-arm may be folded to form a mortise for the reception of the fore-arm tip; Fig. 13, a broken plan view of the front end of a wrought-metal 40 fore-arm, formed by shaping a seamless tube instead of folding a blank; Fig. 14, a view in front elevation of the construction shown by Fig. 13; Fig. 15, a broken plan view of the front end of a wrought-metal fore-arm, the 45 upper face of which is open throughout its length; Fig. 16, a view thereof in front elevation; Fig. 17, a development of such a blank as may be used for the production of the fore-arm shown by Figs. 1 to 9, inclusive.

50 Heretofore tubular-magazine guns have

been provided with wooden fore-arms made by preference of black walnut, which has now grown extremely scarce and expensive and have been found objectionable for a variety of reasons, among which the following may 55 be mentioned: first, liability to split in being fashioned and handled on account of having to be worked down very thin, so as to secure the room required for the accommodation of a tubular magazine or its adjuncts, unless made 60 so large as to be cumbersome and heavy; second, liability to shrink and get loose in dry weather and in wet weather to swell and distort the metal parts and impair the accuracy of the gun; third, liability to be affected by 65 the weather to such an extent that it is impracticable to make them in quantities for stock or faster than they are required for being actually placed in guns; fourth, liability to char in use.

70 The object of my present invention is to avoid the objections, including those above stated, incident to the use of wooden fore-arms in tubular-magazine guns.

75 With these ends in view my invention consists, as a new article of manufacture, in a wrought-metal fore-arm for tubular-magazine guns, the said fore-arm being adapted at its rear end for being operatively connected with the gun frame or receiver.

80 My invention further consists in certain details of construction, as will be hereinafter described, and pointed out in the claims.

85 Wrought-metal fore-arms constructed in accordance with my invention may be produced in a variety of ways and obviously will take a variety of forms as to their details to comply with the varying requirements of different guns. I cannot, therefore, attempt to show or describe all of the forms which my 90 improved wrought-metal fore-arm may assume, but only a few forms which must suffice for the disclosure of my invention.

95 In carrying out my invention as shown in Figs. 1 to 9, inclusive, I produce a chambered wrought-metal fore-arm 2 by bending into shape a blank 3 of the form shown by Fig. 17. The fore-arm 2 in its external appearance corresponds exactly to an ordinary wooden fore-arm, though it may be made and probably 100

will be made considerably smaller than the same in all of its dimensions, thus securing an obvious gain in convenience and appearance. As shown, its side walls are formed with corresponding longitudinal grooves 4, located opposite each other and designed to receive the tips of the fingers in clasping it. The upper edges of the metal are bent or folded inward to form rounded flanges 5, which not only stiffen the structure, but also give the same along its edge an appearance of rigidity and thickness which it would otherwise not have, as the metal used in its construction may not be over two-hundredths of an inch thick. At its front end the side walls of the fore-arm are united by a web 6, concaved to the form of the gun-barrel and formed by riveting and brazing tongues 7 and 8 on the forward corners of the blank 3, as shown by Fig. 17. At its front end the fore-arm is formed with a circular opening 9 for the reception of a ring-shaped tenon-piece 10, which is secured in place by brazing, and the front end of which projects forward beyond the front end of the fore-arm just enough to form a tenon or shoulder 11 to take in tenonwise into a suitable fore-arm tip of any construction and arrangement. At its rear end the fore-arm 2 has a U-shaped opening 12 for the reception of a U-shaped tenon-piece 13, the rear end of which projects beyond the rear end of the fore-arm to form a tenon or shoulder 14, adapted to take tenonwise into a mortise or the equivalent of a mortise in the front end of the gun frame or receiver, which may be of any suitable construction.

A wrought-metal fore-arm constructed as described has the external appearance of a wooden fore-arm and is applied and used in the same way. Over a wooden fore-arm it has the advantage of compactness, durability, lightness, elegance of appearance, and immunity from changes in the weather. At first blush it seems incredible, but it is a fact that the warping or twisting of an ordinary wooden fore-arm may exert such force on a gun-barrel as to bend the same to an extent which will measurably affect the accuracy of the arm. To provide for the swelling and distortion of a wooden fore-arm, it must be made larger than would otherwise be necessary, so as to provide for the required clearance when warped and distorted.

In the construction shown in Figs. 10 and 11 of the drawings separate tenon-pieces, such as 10 and 13, are dispensed with and replaced by front and rear tenons 15 and 16, formed by bending the metal of the fore-arm upon itself, as clearly shown by Fig. 11, which represents the front tenon 15 on a greatly-enlarged scale.

In Fig. 12 the metal at the forward end of

the fore-arm is bent upon itself to form a mortise 17 for the reception of a tenon.

In the construction shown by Figs. 13 and 14 the fore-arm 18 is produced by cutting and shaping a seamless tube, which is cut away from its rear end nearly to its forward end, where a transverse web 19 is left to unite the side walls of the fore-arm at the forward end thereof.

In the construction shown by Figs. 15 and 16 the upper face of the fore-arm 20 is left open throughout its length. In this construction a separate front tenon-piece 21 is used.

Of course a great many variations as to details of construction may be resorted to, and will be resorted to as required by the special guns with which the improved fore-arm may be used. The modifications chosen for illustration will, it is thought, point out the scope of the invention. I would, therefore, have it understood that I do not limit myself to the constructions shown and described, but hold myself at liberty to make such departures therefrom as fairly fall within the spirit and scope of my invention.

Having fully described my invention, what I claim as new, and desire to secure by Letters Patent, is—

1. As a new article of manufacture, a wrought-metal fore-arm for guns, the said fore-arm having its upper longitudinal edges turned inward, and its front and rear ends adapted to be operatively connected with parts of a gun.

2. As a new article of manufacture, a wrought-metal fore-arm for tubular-magazine guns, the said fore-arm being adapted to receive a tubular magazine and having independently-formed front and rear tenon-pieces applied to its front and rear ends for operatively connecting the same with parts of the gun.

3. As a new article of manufacture, a wrought-metal fore-arm for guns, the said fore-arm having its front and rear ends adapted to be operatively connected with parts of a gun, whereby it is firmly supported in place, and having its side walls struck inward.

4. As a new article of manufacture, a wrought-metal fore-arm for tubular-magazine guns, the said fore-arm containing a chamber extending throughout its length for the reception of a tubular magazine and having its side walls united at its forward end and having its front and rear ends provided respectively with independently-formed tenon-pieces which project beyond the front and rear ends of the fore-arm for coupling the same with the gun.

5. As a new article of manufacture, a wrought-metal fore-arm for tubular-magazine guns, the said fore-arm having a cham-

ber extending throughout its length for the reception of a tubular magazine, having its front and rear ends adapted to be operatively connected with parts of a gun, and having its 5 side walls struck inward to form longitudinal grooves which stiffen it and provide grips for it.

6. As a new article of manufacture, a wrought-metal fore-arm having its side walls 10 united at its forward end, and having its front

and rear ends adapted to be operatively connected with parts of a gun, whereby it is firmly supported in place.

In testimony whereof I have signed this specification in the presence of two subscribers. 15

THOMAS C. JOHNSON.
